ATTYS.

UNITED STATES PATENT OFFICE.

JOHN J. HALLIWELL, OF TUCKAHOE, NEW YORK, ASSIGNOR, BY MESNE ASSIGNMENTS, TO R. HOE AND CO., INC., OF NEW YORK, N. Y., A CORPORATION OF NEW YORK.

FOLDING CYLINDER.

Application filed October 15, 1924. Serial No. 743,654.

This invention relates to certain improvements in folding cylinders, particularly folding cylinders for folding very thick products, such as products of over fifty pages.

In folding certain classes of products, particularly products from high speed printing machines, the folding is effected by a rotary folding cylinder provided with a tucking blade which is projected from the cylinder to fold off the product. The product is folded off into the bite of a pair of folding-off rolls. In the usual constructions, these folding-off rolls are inter-gearied and one of them is driven from the cylinder. These rolls are mounted so that they may be separated to fold products of different thicknesses, one of the rolls being usually mounted in spring-seated bearings. This construction is effective for products of a certain thickness; however, where very thick products are to be folded, as, for instance, products of fifty pages, the very thickness of the product causes the gears by which the rolls are driven to move out of mesh, thus stopping the driving of the rolls. To overcome this, gears have been provided for these rolls with very deep teeth. These deep teeth are unsatisfactory, however, as they are liable to injury and, furthermore, it is impracticable to make the teeth deep enough to remain in mesh for handling very thick products.

A special object of the present invention is to provide a simple drive for folding-off rolls of a folding cylinder in which the driving mechanism is so positioned that teeth of ordinary or shallow depth may be used, and in which these teeth will remain in mesh for the maximum thickness of the product for which the machine is capacitated, thus providing a strong positive drive for the rolls.

With this and other objects not specifically referred to, the invention consists in certain novel parts, arrangements and combinations which will be described in connection with the accompanying drawings, and the novel features pointed out in the claims hereunto annexed.

In these drawings,—

Figure 1 is a side view of so much of a

folding cylinder and associated parts as is necessary for an understanding of the invention, and

Figure 2 is a partial side view, partly in section, of the structure shown in Fig. 1, the view being taken on line 2—2 of Fig. 1, looking in the direction of the arrow.

Referring now to these drawings in detail, the parts of the mechanism are supported in side frames, one of which is shown marked 1, of any suitable or desired configuration. Mounted in this side frame is a folding cylinder 2 provided with the usual folding blade 3 which acts to fold off the product into the bite of a pair of cooperating folding rolls 4, 5. Cooperating with this folding cylinder is the usual cutting cylinder 6, and the products are delivered from the folding rolls to a delivery shown as a fly 7.

In accordance with the invention, means are provided for positively driving the folding rolls so that the driving gears will remain in mesh for the maximum movement apart of the rolls for which the machine is capacitated. In the particular construction for effecting this, one of these rolls, as the roll 4, has its shaft 8 mounted in spring-seated bearings, indicated at 9, the roll being moved by the product against the spring as the product passes between the rolls. The other roll is stationarily mounted, the shaft 10 of the roll taking bearing in the side frames of the machine. The stationary roll is driven in the usual manner from the folding cylinder by means of a gear 11 on the folding cylinder meshing with a gear 12 keyed on the end of the roll shaft 10 outside the frame, as shown in Fig. 2. Instead of gearing the rolls 4, 5 directly together, as usual, separate gearing is provided for driving the roll 4 from the roll 5, this gearing being so proportioned and positioned that it remains in mesh within the limits of the movement of the roll 4. In the particular construction shown, the shaft 10, inside the frame, is provided with a gear 13 which is in mesh with an intermediate 14 on a stud 15. The gear 14 is in mesh with a second intermediate 16 on a stud 17. These studs are suitably supported in the machine, as in a bracket 18 secured in the machine frame.

The intermediate 16 is in mesh with a gear 19 on the shaft 8 of the roll 4. It will be noticed that the axes of the shaft 8 and the stud 17 are in the same vertical plane, but 5 that the axis of the stud 15 is offset to one side of the axis of shaft 10. It follows that when the roll 4 is moved the gear 19 is in mesh with the gear 16 at any point in the movement of the roll, so that the gears are 10 always in mesh and the rolls may be positively driven with shallow-tooth gears no matter what the thickness of the folded product may be within the limits of the mechanism.

15 It will be observed, see Fig. 2, that the gears 13 and 19, which drive the rolls 5, 4, are of smaller diameter than the rolls, so that these gears are never in mesh, the driving being from 13 through 14 and 16 to 19.

20 By thus arranging the parts, the gears can all be in the same vertical plane and a good drive assured without danger of jamming the gears, and space is economized, which is important in this class of machines. Furthermore, the gears may be placed inside the frames and closely adjacent the ends of the rolls, thus insuring an effective drive.

While the invention has been shown and described in its preferred form, it will be understood that certain minor variations may be made in the form and arrangement of the parts without departing from the invention, 30 as defined in the appended claims.

What I claim is:

1. In a folding mechanism, the combination of a folding cylinder having a driving gear, a pair of folding rolls directly cooperating therewith and mounted to separate to fold products of different thicknesses, gears on the rolls of smaller diameter than the rolls so as to be out of mesh with each other, an additional gear for one of said rolls which gear is in mesh with the driving gear on the cylinder, and driving gears independent of the rolls and arranged in the same plane as the roll gears and positioned to be in mesh with the roll gears at any point in the separating movement of the rolls. 35

2. In a folding mechanism, the combination of a folding cylinder, a pair of folding rolls directly cooperating therewith and mounted to separate to fold products of different thicknesses, framing in which the folding rolls are mounted, a driving gear on the folding cylinder, a gear on one of the folding rolls meshing therewith outside the framing, gears on the rolls inside the framing of smaller diameter than the rolls so as to be out of mesh with each other, and a pair of driving gears arranged in the same plane 55 as the roll gears and position to be in mesh at any point in the separating movement of the rolls. 60

In testimony whereof, I have hereunto set my hand.

JOHN J. HALLIWELL.
